UNITED STATES PATENT OFFICE.

HENRY HIPKINS, OF BIRMINGHAM, COUNTY OF WARWICK, ENGLAND.

SLEEPER.

SPECIFICATION forming part of Letters Patent No. 396,160, dated January 15, 1889.

Application filed May 29, 1888. Serial No. 275,488. (No model.) Patented in England February 23, 1888, No. 2,716.

To all whom it may concern:

Be it known that I, HENRY HIPKINS, of Belvue Hotel, Congreve Street, Birmingham, in the county of Warwick, England, boiler manufacturer, and a subject of the Queen of Great Britain, have invented certain new and useful Improvements in Sleepers, (the same having been patented in England February 23, 1888, by Letters Patent No. 2,716;) and I do hereby declare that the following is a sufficient description of the invention to enable those skilled in the art to which it appertains to carry the same into practical effect.

My invention has for its object improvements in sleepers which are specially applicable for light railways or tramways—such, for instance, as colliery work—where the speed is slow and horse-power is generally used; but the principle would be the same for heavier traffic.

I make my sleepers from a sheet or strip of metal—say steel, wrought-iron, or other wrought metal—and I press it in molds so as to have its edges turned down, and, when necessary, its back curved over or corrugated longitudinally. At each end I provide hook clips or jaws for the rail by pressing upward two ears or projecting lips out of the solid metal in such a manner that the rail will slide in under the lips, or the sleepers are threaded upon the rails. These lips or jaws are strengthened by corrugations or brackets, also pressed up out of the hollow at the back of each jaw, which greatly stiffens them. A center strip is left, upon which the rail rests, as well as upon the metal at each side of the sleeper. I thus dispense with all rivets or loose parts, and obtain a cheap sleeper at a minimum cost.

In order that my invention may be clearly understood and more easily carried into practical effect, I have appended hereunto a sheet of drawings, upon which I have shown five figures, which illustrate the same in several forms, which will enable others to adapt the principle to the varying conditions met with in practice—such, for instance, as sandy or stony ballast, or for railways, tramways, or colliery purposes.

Figure 1 is a side elevation of a sleeper, E, showing the end of each rail C and C' in position. Fig. 2 is a plan of the sleeper E with-

out the rails C and C', in order that the strip e' may be more clearly seen. Fig. 3 is an actual section of the sleeper through A B, 55 showing the bent edges e² and e³ and the single center corrugation, e⁴. Fig. 4 is a similar section to the previous figure, but shows how two corrugations, e⁵ and e⁶, may be made instead of one, and it will be well understood 60 that more than two corrugations may be easily made with suitable tools. Fig. 5 shows one end of a sleeper only—i. e., with the center part cut out—as metal may thus be sometimes saved—that is, by using only occasionally a long sleeper, as shown by Figs. 1 and 2, and also sometimes the pieces, Fig. 5, may be fastened to wood sleepers by the holes e⁷, or a tie bar or strip of metal may be used to connect the two for the purpose of maintaining 65 an accurate gage.

These sleepers are made from one piece of metal, the jaws e⁸, e⁹, e¹⁰, and e¹¹ being stamped out and raised from the plate in a suitable press, hydraulic or otherwise. When these 75 jaws are so raised, a cross-strip, e', is left to connect the two sides of the sleeper for stability and bearing for the base of the rail, and this strip may be hollowed or corrugated lengthwise to stiffen it to prevent any buckling when 80 a hammer is used to knock it on or off the rail. The strip may be of any width to suit the design of the rail. The ribs e¹² are raised for the purpose of stiffening the jaws e⁸ e⁹ e¹⁰ e¹¹, and there may be one, two, or more of them, ac- 85 cording to design and the number of corrugations in the sleeper. These ribs may be used to strengthen the jaws without the cross-strip e', as that may in some cases be dispensed with, and likewise the cross-strip e' 90 may sometimes be used with jaws without ribs. The ends e¹³ e¹⁴ may also be turned down to hold the ballast when required, and in the case of Fig. 5 all the edges may be turned down. It will thus be seen that there 95 are gaps K in the sleeper under the rail, which remain from pressing up the jaws; but these are covered by the rail, which takes its bearing upon the two outer edges of the sleeper, whether short or long.

100

I prefer making the sleepers from soft steel; but of course other suitable metal capable of being worked may be used.

What I claim, then, is—

A metallic sleeper in one piece, provided
near its ends with pairs of raised jaws for
holding the rails and ribs e^{12} for bracing said
jaws, said sleeper also having a raised rib, e^4 ,
5 extending lengthwise of said jaw as far as the
inner ends of said ribs e^{12} , for the purpose set
forth.

In testimony that I claim the foregoing as
my own I affix my name in the presence of
two witnesses.

HENRY HIPKINS.
